UNITED STATES PATENT OFFICE.

HORACE PECK CARVER, OF RACINE, WISCONSIN.

DESIGN FOR A SAD-IRON.

SPECIFICATION forming part of Design No. 23,067, dated February 13, 1894.

Application filed January 5, 1894. Serial No. 495,870. Term of patent 14 years.

To all whom it may concern:

Be it known that I, HORACE PECK CARVER, a citizen of the United States, residing at Racine, in the county of Racine and State of Wisconsin, have invented and produced a new and original Design for Sad-Irons; and I do hereby declare the following to be a full, clear, and exact description of the same, reference being had to the accompanying drawings, forming a part thereof.

My invention is a new and original design for a sad iron, and is illustrated in the accompanying drawings, in which—

Figure 1 is a perspective view of a sad iron embodying my design, and Fig. 2 is a longitudinal sectional view through the polishing surface thereof.

The leading feature of my design is a sad iron, provided with a convex, polishing surface having concave or sunken grooves or

lines thereon as shown. These concave lines or depressions are arranged as shown in the drawings in which are shown a series of pairs of parallel straight grooves *a a* or lines, and between each pair of parallel grooves is a zigzag or angular groove *b*, and there is also one of said zigzag grooves outside the pair of parallel grooves at each end of the polishing surface as shown at *b' b'*.

What I claim, and desire to secure by Letters Patent, is—

The design for a sad iron herein shown and described.

In testimony whereof I affix my signature in presence of two witnesses.

HORACE PECK CARVER.
